UNITED STATES PATENT OFFICE.

EDWARD A. ROBINSON, OF MONTREAL, QUEBEC, CANADA.

GUIDED RAILWAY CONNECTER HEAD.

Application filed November 13, 1926. Serial No. 148,142.

My invention relates to train pipe connectors and more particularly to guiding and supporting means for connector heads.

A purpose of my invention is to have a 5 rearwardly extending support for the head universally seat and pivot on and along a horizontal guide extending longitudinally forward from a bracket.

A further purpose is to provide a sliding 10 head support with a bearing upon and vertical pivoting between transversely spaced guide members extending horizontally forward from a bracket fixed to the train and giving a nearly universal joint within the 15 range of angular movement contemplated.

A further purpose is to limit the forward position of a head support pressed forwardly by a spring and seating and pivoting on and along a horizontal guide extending forward 20 from the bracket by means of a tie.

A further purpose is to use a flexible tie through the center of a buffer spring to limit its extension.

Further purposes will appear in the specification and in the claims.

I have preferred to illustrate my invention by one form only, selecting a form which is practical, efficient and inexpensive, and which at the same time well illustrates 30 the principles involved.

Figure 1 is a side elevation of a connector equipped with my invention.

Figure 2 is rear end elevation of the structure shown in Figure 1 omitting the head.

Figure 3 is a section of Figure 1 taken upon the line 3—3.

Figure 4 is a fragmentary top plan view from the position of the line 4—4 but showing the guide ends closed as distinguished 40 from the open ends in Figures 1—3.

Like numerals refer to like parts in all figures.

Referring to the drawings and describing in illustration and not in limitation:—

45 The connector head 15 is carried on a head support 16 which pivots on and along a horizontal guide 17 extending forwardly from a bracket 18.

A buffer spring 19, compressed between 50 the forwardly directed socketed face 20 of the bracket and the rearwardly directed socketed face 21 of the head support, presses the head support forwardly with respect to the bracket, the forward position being limited 55 by a flexible tie 22 between the support and bracket coaxial with the spring.

The bracket and guide are preferably an integral casting in which the guide comprises oppositely placed (here upper and lower) horizontal forwardly extending pairs of parallel horizontally spaced guiding members 23, 24 and 25, 26 respectively.

The upper and lower pivot projections 27 and 28 from the head support are supported and guided between the respective pairs of 65 guides 23, 24 and 25, 26.

The pivot projections 27 and 28 may to advantage flange spherically at their inner ends to form curved bearing surfaces 29 and 30 which seat respectively against the under 70 sides of the upper guide members and the upper sides of the lower guide members.

The pivot projections 27 and 28 and the spherically seating bearing surfaces 29 and 30 are preferably integral with the head 75 support.

The upper and lower diagonally opposite arms 31 and 32 of the head support fasten to the head by means of bolts 33 in the way shown in my prior application Serial No. 80 610,718 to which the structure otherwise bears some resemblance.

The bearing surfaces 29 and 30 with their projecting pivots 27 and 28 preferably extend to the rear of the body 21 of the head 85 support as illustrated in the drawings to give greater freedom of movement to the head.

The flexible tie as shown comprises hook bolts 34 and 35 at the bracket and head 90 support respectively, held together by chain links 36. Nuts 37 over washers 38 provide means for anchoring the hook bolts, for adjustably controlling the length of the tie and for relieving the compression of the 95 spring to permit more easy assembly or disassembly.

The chief function of the tie is that of limiting the forward position of the head. While I can do this in other ways (as by 100 transversely joining the horizontally spaced guide members in front of the pivots) I prefer the tie in that its use permits such easy longitudinal adjustment and relief of the spring compression for assembly and 105 disassembly.

I show the outer ends of the horizontally spaced guide members 23, 24 and 25, 26 respectively open in the main views that is not joined together in front of the respective 110 pivots, so that in assembly and disassembly the pivots may slide to and out of place

between the open ends 39 and 40 but recognize that the strengths of these arms against vertical and lateral strains may be greatly increased by joining their ends, as at 41 in 5 Figure 4 whether this be used to limit movement or not.

In view of my invention and disclosure variations and modifications to meet individual whim or particular need will doubtless 10 become evident to others skilled in the art and I claim all such in so far as they fall within the reasonable spirit and scope of my invention.

Having thus described my invention, what 15 I claim as new and desire to secure by Letters Patent is:

1. In a train pipe connector, a head, a rearwardly extending support therefor, an upper and a lower vertical pivot projection from each of vertically opposite sides thereof, a forwardly and rearwardly extending bracket and guide member laterally engaging opposite sides of each projection, sustaining the weight of the support and having 20 a forwardly directed face to the rear of the support, a compressed spring between the face and the support pressing the support forwardly, and means connecting through the spring with the rear portion of 25 the bracket member and limiting the forward position of the support.

2. In a train pipe connector, a head, a rearwardly extending support therefor, a downwardly extending pivot projection from the support, a guide seating and guiding the support and having parallel horizontal rearwardly extending walls laterally engaging opposite sides of the projection, a bracket rigidly carrying the guide and having 35 a forwardly directed face rearward of the support, a compressed spiral spring between the face and the support forwardly pressing the support, and a flexible tie between the support and the face limiting the 40 forward position of the support.

3. In a train pipe connector, a head, a rearwardly extending support therefor, an upper and a lower vertical projection from vertically opposite sides thereof, a forwardly and rearwardly extending guide member laterally engaging opposite sides of each projection sustaining the weight of the support and having a forwardly directed face rearward of the support, a spring compressed between the support and the face, a chain surrounded by the spring having ends respectively fastened to the support and to the guide limiting the forward position of the support with respect to the face, and a 45 bracket fixed to the train and carrying the guide.

4. In a train pipe connector, a head, a rearwardly extending support therefor, a downward vertical pivot projection from the support, a guide seating and guiding the support and having parallel horizontal rearwardly and forwardly extending portions laterally slidingly engaging opposite sides of the projection, a bracket fixed to the train and having a forwardly directed face rearward of the support, a spiral spring compressed between the support and the face, a flexible tie between the face portion of the bracket and the support limiting the extension of the support with respect to the face, 70 and a screw adjustment of the effective length of the tie adapted to relieve the compression of the spring.

5. In a train pipe connector, a head support, pivot projections upon vertically opposite sides thereof, an integral bracket and guide comprising a transverse portion rearward of the support, an upper guide portion having horizontally forwardly extending vertical faces making longitudinally sliding lateral engagement with the upper projection, and a lower guide portion having horizontally forwardly extending parallel faces making longitudinally sliding engagement with the lower projection, a flexible tie between the support and the transverse portion of the bracket, and a spiral spring surrounding the tie and compressed between the transverse portion and the support.

6. In a train pipe connector, a head support, a bracket fixed to the train and comprising a transverse portion rearward of the support and vertically spaced guides extending respectively from above and below the transverse portion and each presenting horizontally spaced parallel longitudinally extending guide portions, a vertical pivot between and engaging the upper guide portions, a vertical pivot between and engaging the lower guide portions, a spherical bearing carrying each pivot, forwardly rigidly connected to the support and making spherical bearing engagement with the respective guide portions, a spring compressed between the support and transverse portion, and means limiting the forward position of the head support with respect to the bracket.

7. In a train pipe connector, a bracket fixed to the train, a pair of horizontally spaced guides extending horizontally forward from the bracket, a head supporting member seating on and vertically pivoting between the guides, means forwardly pressing the member, and other means longitudinally adjustable limiting the forward position of the member along the guide.

EDWARD A. ROBINSON.
